UNITED STATES PATENT OFFICE.

WILLARD B. FEATHERSTONE, OF WASHINGTON, DISTRICT OF COLUMBIA, ASSIGNOR TO
ARTHUR C. BROWN, TRUSTEE, OF KANSAS CITY, MISSOURI.

ACOUSTIC APPARATUS.

1,123,185.

Specification of Letters Patent. Patented Dec. 29, 1914.

Application filed November 17, 1910. Serial No. 592,908.

To all whom it may concern:

Be it known that I, WILLARD B. FEATHERSTONE, a citizen of the United States, residing at Washington, in the District of Columbia, have invented certain new and useful Improvements in Acoustic Apparatus, of which the following is a specification.

My invention relates to the distribution of sounds, particularly behind a screen on which pictures are projected, and has for its object to make it appear to the audience that the sounds are produced by objects at various places in the scene. I accomplish these results by the improved apparatus described below and shown in the accompanying drawing, in which:

Figure 1 represents a screen on which pictures are projected, and a frame for supporting sound-outlets. Fig. 2 is a top view of the screen and some of the sound-outlets and a phonograph. Fig. 3 shows parts of the projecting and reproducing apparatus in operative relation to the parts shown in Fig. 2 and Fig. 4 shows an interrupter or switch in the form of a dial.

In Figs. 1 and 2, A is a screen to receive pictures projected by the stereopticon or motion picture machine, G, Fig. 3.

B, B, Figs. 1 and 2, are sound-outlets, preferably horns attached directly to loud-speaking telephone receivers C, C. These sound-outlets are distributed over the back of the screen in any desired arrangement, as instanced by the numerals 1, 2, 3, 4, 5, 6 and 7, in Fig. 1, the arrangement being made with the object of having the sound appear to come from the picture of the object supposed to produce it.

H, H, Fig. 3, are phonographs or the like whose reproducers R, communicate with, or are combined with the transmitters, Q, of a telephone system which includes the loud-speaking receivers, C, C. Any well known means may be provided to run the phonographs synchronously with the motion-picture projector.

The interrupter J, Fig. 4, is placed at a suitable part of the telephone system, and has a plurality of points, L, L, adapted to close the circuits by contact with the conductor K.

The operation of my apparatus is as follows: The interrupter J, is prepared by arranging the points L, L, so that any given point shall remain in contact with the

conductor K, only during intervals when it is desired that the audience shall hear sounds coming from the sound-outlet controlled by that point. Thus upon revolution of the interrupter disk J, or the conductor K, the raised parts of the disk (shown in black in Fig. 4) will be in contact with the conductor K only when directly beneath it. At other times the circuit is temporarily broken or interrupted, and at such other times consequently no sound will issue from the corresponding sound-outlets behind the screen. The source of the sounds usually will be one or more phonographs or the like, H, H, Fig. 3, and these, together with the interrupter, are preferably direct-connected with the motion-picture mechanism G, with an intervening differential W, Fig. 3, to preserve synchronism by varying the speed of the motion-picture mechanism, should the two devices get out of step. The sounds emanating from the reproducers R, R, enter the telephone system through the transmitters Q, Q, and each transmitter may be connected to serve a selected few of the receivers C, C, as for instance those supplying sound-outlets 1, 2, 3, 4, and 5, Fig. 1, or 16, 17, 18, 19 and 20, as it often is desirable to supply the latter group with orchestra music from a stock record, while the other groups may be supplied from special records. The disk J, Fig. 4, is shown divided into four concentric groups, M, N, O and P, of 5 rings each, the rings being broken points of contact adapted to connect with the respective parts, M', N', O', and P' of the conductor K. This arrangement permits the sounds from each phonograph record to be conveyed to a different group of sound outlets, to be further isolated and distributed by the individual points L, L. Suppose now that there is being shown on the screen a motion-picture of a comic opera. The interrupter J and conductor K, are in the positions shown in Fig. 4, and the conductor starts revolving to the left. The first points to be in contact are those in group M, supplying outlets 16, 17, 18, 19 and 20 with orchestra music for, say, nearly a minute, while the pictured curtain is down and the orchestra, also in picture, is seen playing upon instruments whose sounds as above supplied appear to come from that part of the screen. Soon the curtain rises and the

chorus appears in full song, supplied by all of the outlets corresponding with group N, except 13, which is silent, awaiting the entrance of the leader, or heroine, who soon appears and sings a solo to a diminished or-
 5 choral accompaniment, as indicated in Fig. 4, on sector III of the interrupter disk. The chorus and orchestra now take up the chorus of the song, this interval being indicated by the full black on the second half
 10 of sector III. Now the chorus withdraws and another character, the hero, appears in the background, singing as he approaches, his path being roughly indicated by the numbers 1, 6, 7 and 12 on the screen. The heroine meantime utters an occasional re-
 15 mark, which is conveyed to the audience only by the outlet 13, while the hero's song is conveyed successively by outlets 1, 6, 7,
 20 and 12, which are controlled by the points indicated in black in sector IV of disk J, Fig. 4. A dialogue now ensues between the two characters, who are pictured with their heads approximately at 12 and 13, Fig. 1.
 25 Now another character enters at 10 and approaches to 14, all of these movements being faithfully followed by the prepared interrupter, as indicated on sector V, Fig. 4. A fourth character enters at 11, and the quar-
 30 tet sings a couple of stanzas to the accom-
 paniment of the orchestra, (sector VI). Then the chorus appears for the tableau, (sector VII) and the curtain drops on the first scene. The orchestra now plays an in-
 35 terlude, (sector VIII).

I claim:

1. An apparatus for reproducing and distributing sounds, comprising a series of sound records, a series of telephone circuits, 40 the transmitters of said circuits being operatively positioned with respect to said records, a series of loud-speaking receivers spaced apart to provide a series of distinguishable sound outlets, and an automatic 45 switch between said transmitters and said receivers, whereby the sounds are caused to emerge from any desired outlet, substantially as described.

2. An apparatus for reproducing and distributing sounds with animated pictures, comprising a sound record, a telephone circuit, the transmitter of said circuit being operatively positioned with respect to the sound record, a conductor connected to said 55 transmitter, a plurality of contact surfaces adapted to engage with said conductor, a series of loud-speaking receivers, said receivers being connected to said contact surfaces, whereby the engagement of the conductor with said surfaces connects selected 60 of said receivers to arrange the points of sound emergence in accordance with the projected picture, substantially as described.

3. In an apparatus for reproducing and 65 distributing sounds, the combination of a

sound record, a series of sound outlets ar-
 ranged apart a distinguishable distance, and
 means acting automatically for causing the
 sound to emerge from any selected of said
 outlets to arrange the points of sound emer-
 gence as desired, substantially as described. 70

4. In an apparatus for reproducing and distributing sounds with animated pictures, the combination of a sound record, a series of sound outlets, a telephone circuit between 75 the record and the outlets, an automatic switch controlling the circuit to cause the sound to emerge from desired outlets, where-
 by the points of sound emergence are ar-
 ranged in accordance with the projected 80 picture, substantially as described.

5. In an apparatus for reproducing and distributing sounds, the combination of a series of sound records, a series of conductors, a series of telephone circuits, the transmitter 85 of each circuit being connected to a conductor and in operative relation to a sound record, a series of loud-speaking receivers arranged apart to provide a series of dis-
 tinguishable sound outlets, an interrupted 90 contact surface for each conductor, a con-
 nection between said contact surfaces and
 said receivers, said contact surfaces and
 said conductors being movable with respect
 to one another, whereby the receivers are 95 connected up with the transmitters to ar-
 range the points of sound emergence as de-
 sired, substantially as described.

6. In an apparatus for reproducing and distributing sounds with animated pictures, 100 the combination of a series of sound rec-
 ords, a member divided into a series of sec-
 tions, each constituting a conductor, a series
 of telephone circuits, the transmitter of each
 circuit being connected to a conductor and 105 operatively positioned with respect to a
 sound record, another member movable with
 respect to the conductors and divided into
 a series of interrupted contact surfaces
 adapted to be engaged by said conductors, a 110 series of loud-speaking receivers, said receiv-
 ers being connected to said contact surfaces,
 whereby when said conductors and contact-
 surfaces are moved with respect to one an-
 other, selected receivers are connected up 115 with said transmitters to arrange the points
 of sound emergence in accordance with the
 projected picture, substantially as described.

7. An apparatus for reproducing and distributing sound, comprising a talking ma-
 chine, a telephone circuit having a transmitter 120 operatively positioned with respect to the record of the talking machine, a plu-
 rality of receivers arranged apart a dis-
 tance to provide distinguishable sound out-
 lets, an automatic switch controlling the 125 circuit and operated in conjunction with the
 talking machine, the contacts of said switch
 being arranged in accordance with a pre-
 arranged program, whereby selected of said 130

receivers are connected up with said transmitters at the prearranged times, substantially as described.

8. An apparatus for reproducing and distributing sounds, comprising a plurality of sound records, a plurality of telephone circuits, each having a transmitter operatively positioned with respect to a record, a plurality of receivers spaced apart to provide a series of distinguishable sound outlets, and means for connecting up any selected receiver with a selected sound record, substantially as described.

9. The combination with a talking machine having a sound record device; of variously located enouncers; electrical transmitting means connected with the enouncers respectively; and an automatic switching device operatively connected with the sound record device for the purpose of distributing various portions of the recorded sounds from the transmitting means to the various enouncers respectively.

10. The combination with a sound record device containing a sound record having successively arranged individual characteristic parts; of means to reproduce said parts from such sound record; separately disposed enouncers; means to transmit the reproduced sound record from said record reproducing means to the enouncers; and means acting automatically to distribute the said individual characteristic parts of the record successively to predetermined enouncers.

11. A phonograph or talking machine having combined with its sound-reproducing diaphragm an electrical transmitter capable of changing the mechanical vibrations of the phonograph or talking machine diaphragm into electrical impulses of like intensity and duration so as to re-

produce the vibrations of the phonograph or talking machine diaphragm on a receiver diaphragm reproducer operated by the current in the circuit of the electrical transmitter, a plurality of such diaphragm reproducers, means for transferring the current to two or more of said reproducers at a desired distance from said talking machine or phonograph and means for intermittently operating singly either of the two or more reproducers as predetermined for the purpose of changing the location or placement of said sounds reproduced by said phonograph or talking machine, to have said sounds seem to emanate from such characters or objects as are supposed to be the original utterers of said sounds.

12. In combination with a sound record and means for reproducing said record, enouncers, electrical circuits between the reproducing means and the enouncers, and a switching device for said circuits, said switching device having periods of contact of the length of such portions of the sound record as it is required to divide the said sound record into.

13. In combination with a sound record and means for reproducing said record, a switching device having periods of contact of the length of such portions of the said sound record as it is required to divide said sound record into, means to operate said switch device in register with the movement of said sound record, an electrical transmitter, electrical receivers, and circuits therefor; said circuits being controlled by the switching device.
